UNITED STATES PATENT OFFICE.

FREDERICK R. PARKER, OF CHICAGO, ILLINOIS.

SAFETY-VALVE.

1,106,108.

Specification of Letters Patent.

Patented Aug. 4, 1914.

Application filed September 18, 1909, Serial No. 518,306. Renewed January 8, 1914. Serial No. 811,100.

To all whom it may concern:

Be it known that I, FREDERICK R. PARKER, a citizen of the United States of America, residing at Chicago, in the county of Cook 5 and State of Illinois, have invented a new and useful Safety-Valve, of which the following is a specification, reference being had to the accompanying drawings, illustrating same.

10 My invention relates to valves for controlling the flow of fluid, either liquid or gaseous, and has for one of its principal objects the provision of improved mechanism whereby a reduction of the pressure of the 15 fluid to zero or to any predetermined value causes the automatic operation of the valve, preferably closing the valve.

Another object is to provide improved valve-operating mechanism of the character 20 hereinafter set forth.

Another object is to provide an improved automatic pressure-controlled valve which is capable of manual operation at all times.

Another object is to provide an improved 25 thumb leaf, or the like, for valves of the character herein set forth, which, when accidentally struck, tends to act against operating the valve; the thumb leaf at the same time permitting of certain accidental operation thereof, to protect the mechanism from 30 injury.

Another object is to provide improved means for causing the fluid pressure to control a diaphragm, and improved means 35 whereby the diaphragm automatically controls the valve-operating mechanism.

Another object is to provide improved means for adjusting the valve-operating spring mechanism in a valve of the character 40 hereinafter set forth.

Another object is to provide simplicity, durability, and efficiency in such valves.

Other objects will be apparent from the following specification.

45 In the drawings, illustrating one form of my invention, Figure 1 is a cross-sectional view of a certain type of the improved valve of this invention, showing the interior construction thereof, with portions shown in elevation; Fig. 2 is a bottom view of the valve of Fig. 1; Fig. 3 is an elevation of a portion of the valve casing shown in Fig. 1; and Fig. 4 is a plan view of a portion of the valve-operating mechanism shown in 50 Fig. 1.

Like characters refer to like parts in the several figures.

It is well known that with ordinary gas valves a reduction of the gas pressure to zero while the valve is open and the gas is 60 lighted, causes the light to be extinguished; and that if the gas pressure comes on again after the light has been extinguished in this manner the gas will escape from the open gas jet into the surrounding space. Such a 65 condition is very dangerous to life and property and is one which has to be constantly contended with. Many are the fatalities caused by just such conditions.

In this present invention I have provided 70 means for entirely eliminating the above-mentioned dangerous condition, and have provided a valve through which the escape of gas is impossible after the gas pressure has been reduced sufficiently to extinguish 75 the light, or reduced to a dangerous degree. This and other improvements, as well as various modifications thereof, are what are contemplated in this invention. The value of such improvements can be readily seen, 80 and readily understood from the following detailed description of one form of my invention.

In this invention I cause the pressure of the fluid which is controlled by the valve, to 85 control mechanism which automatically holds the valve open after being suitably opened, and arrange this mechanism so that it will automatically close the valve when the fluid pressure (or a portion thereof) is 90 removed therefrom. I also preferably arrange this mechanism so that it is capable of manual operation, independently of the automatic operation caused by the fluid pressure. Thus it will be seen that the valve-operating mechanism is capable of a double 95 usage, a manual operation and an automatic operation.

By reference to the accompanying drawings, 1 is the valve casing which is provided with an inlet passage 2 and an outlet passage 3.

4 is the valve plug which is preferably provided with a ground tapered portion 5 adapted to fit in a ground tapered plug seat 105 6 in the casing 1 as shown. The tapered plug seat 6 has an opening 7 extending therefrom to accommodate the long straight part 8 of the plug 4. The plug 4 forms an obstruction between the passages 2 and 3 110

when seated in its seat, to prevent the flow of fluid through the valve. The plug 4 is provided with a hole 9 extending longitudinally therethrough, and a hole 10 extending transversely therethrough and intersecting the hole 9. It will now be readily seen that when the plug 4 is raised from its seat 6 as shown in dotted lines at 11, and turned so that the hole 10 is in alignment with the hole 3, the passage through the valve will be opened so as to permit the flow of fluid therethrough.

For manually operating the valve plug 4 I provide a pair of arms 12 12 loosely pivoted to a supporting cross bar 14 at 13 13, the lower ends of the arms 12 12 preferablylapping over each other as shown at 15 to provide a suitable thumb leaf. The cross bar 14 is carried by the plug 4, being preferably screwed thereon as shown and held against further turning thereon preferably by a set-screw 16. The upper ends 21 21 of the arms 12 12 are adapted to be turned around in the annular recesses 17 and 18 in the casing 1. The recesses 17 and 18 are preferably connected together by a pair of passageways 19 in the annular projection 20 which separates the recesses 17 and 18, to permit the upper ends 21 21 of the arms 12 12 to pass from one of the said recesses 17 18 to the other when the arms 12 12 are turned to a position approximately around 90 degrees from the position shown in Fig. 1.

To the lower end of the plug 4 I attach a member 22 carrying a flexible diaphragm 23 and forming the wall of a chamber 24 into which the hole 9 through the plug 4 opens. The diaphragm 23 may be secured to the wall member 22 in any suitable manner, preferably by forming the edge of the wall member 22 over as shown, tightly against the diaphragm 23, and sealing the joint between the wall member 22 and the diaphragm 23 by some suitable sealing material. The wall member 22 is preferably screwed onto the end of the plug 4, against the cross bar 14, and may, if desired, form a lock nut for the bar 14 to prevent it from turning. Loosely pivoted to the respective arms 12 12 at 25 25 are a pair of links 26 26, these links being loosely pivoted together as at 27. When the diaphragm 23 is forced outwardly to the position 28 shown in dotted lines, preferably against the links 26 26, the latter are held in their full-line positions 26 26, so as to hold the arms 12 12 in their full-line positions and thus hold the ends 21 21 of the arms 12 12 in one or the other of the annular recesses 17 18. If the links 26 26 are moved to their dotted-line position 29, the lower portions of the arms 12 12 will be drawn inwardly so as to move the upper ends 21 21 of the arms 12 12 outwardly, out of the annular recess 17 or 18.

65 Around the portion 8 of the plug 4 are

preferably placed a suitable packing material 30, a ring 31 acting on the packing material 30 to suitably hold same in place, and a coil spring 32 acting between the ring 31 and the cross bar 14. The spring 32 serves to suitably compress the packing material 30 in place, and also to automatically seat the plug 4 in the seat 6 when not prevented from doing so by the ends 21 21 of the arms 12 12 engaging the annular projection 20 in the annular recess 18, as shown at 36 36 in Fig. 1. Thus it will be seen that the spring 32 makes a plunger out of the plug 4. I preferably inclose the spring 32 by a casing 33 to protect it, the casing 33 sliding in a recess 34 in the valve casing 1 when the plug 4 is raised from or lowered into its seat 6. I wish it to be understood that I can readily adjust the tension of the spring 32 acting on the plunger 4, if desired, by a suitable nut screwed onto the plunger 4 against the action of the spring 32. The cross bar 14 may, if desired, serve as this adjusting nut. Over the upper end of the plug 4 I preferably place a cap nut 35 which may be removed to permit of removing the plug 4 from, or placing it into the casing 1.

For operating the diaphragm 23 I preferably use the fluid pressure in the pipe leading to the valve inlet passage 2. Normally the diaphragm is preferably in the retracted position 23, but when the plug 4 is raised from its seat 6 the fluid pressure is transmitted from the inlet pipe (not shown) through the inlet passage 2 and the hole 9 in the plug 4 to the chamber 24 and the diaphragm 23, thus forcing the latter out to the position 28 and thereby holding the links 26 26 in their lower full-line position and consequently the ends 21 21 of the arms 12 12 in the annular recess 18, provided they are not directly over the passageways 19. Thus it will be seen that the fluid pressure acting on the diaphragm 23 holds the plug or plunger 4 in its raised position, out of its seat 6. The plug 4 will be held in this raised position whether it is turned to fully open the valve passage or not, the outlet passage 3 being preferably small enough, in comparison with the inlet passage 2 and the hole 9, to not materially reduce the fluid pressure in the hole 9 and the chamber 24 when fully opened. Now if by any means the pressure of the fluid in the inlet pipe becomes reduced, the fluid pressure in the chamber 24 will be correspondingly reduced. Therefore, if the pressure of the fluid in the inlet pipe becomes reduced sufficiently, either to zero or to any predetermined value, there will be nothing to hold the diaphragm 23 in the position 28 against the action of the spring 32 which tends to seat the plug 4 and thereby force the ends 21 21 of the arms 12 12 outwardly from their positions 36 36 in the recess 18, over the beveled surfaces 37 37 of 130

the annular projection 20 to their positions 21 21 shown in Fig. 1, in the meantime the links 26 26 moving to their position 29 as the ends 21 21 of the arms 12 12 slide over the beveled surfaces 37 37, thereby forcing the diaphragm 23 inwardly to its full-line position. This, then, is the operation that automatically takes place when the fluid pressure is sufficiently reduced. As soon as the valve has been automatically closed as just described, the links 26 26 and the arms 12 12 again take their full-line positions shown in Fig. 1, due to the weight of the portions 38 38 of the arms 12 12, and the weight of the links 26 26, all of which tend to move the ends 21 21 of the arms 12 12 inwardly. If desired, however, suitable spring mechanism may be employed to normally hold the end portions 21 21 of the arms 12 12 inwardly. Thus it will be seen that the plug 4 cannot be again raised from its seat until the arms 12 12 are turned so that the portions 21 21 may pass through the passageways 19 to the recess 18.

To prevent accidental opening of the valve I preferably cross the portions 38 38 over each other as shown, the outer edge 39 of each portion 38 forming a protection or shield for the corresponding edge 40 of the opposite arm 12. This prevents accidental striking of the edges of the thumb leaf 15 from tending to open the valve, as the striking of either edge portion 39 tends to throw the end 21 of the same arm 12 inwardly, instead of outwardly as would be the case if the portions 38 38 were not crossed over. This crossing-over of the portions 38 38 also provides a thumb leaf 15 the grasp of which tends to hold the arms 12 12 in the full-line positions shown in Fig. 1, relatively to the plunger 4, while the valve is being manually operated.

The valve may be manually opened by turning the arms 12 12 so that the portions 21 21 thereof may pass through the passageways 19, then raising the arms 12 12 with the plug 4 so that the portions 21 21 pass through the passageways 19 from the recess 17 to the recess 18, and then turning the arms 12 12 with the plug 4 to regulate the outlet passage from the hole 10 to the hole 3 as desired. It will be readily understood that the outlet passage may be manually regulated to reduce the flow of fluid through the valve as much as desired without the pressure-controlled mechanism causing the valve to automatically close, as the pressure, remaining practically the same, acts continually during such manual regulation to lock the valve plug against being seated. If, however, the arms 12 12 are turned so that the portions 21 21 may pass through the passageways 19 from the recess 18 to the recess 17, the spring 32 will automatically seat the valve plug or plunger 4. When the plug

4 is seated, the thumb leaf 15 and arms 12 12, with the plug 4, are free to turn around if accidentally struck, without opening the valve. This prevents the injury of these parts because they yield to the force instead of breaking as they might if not capable of being turned. Thus it will be seen that the valve is capable of manual operation and regulation independently of the automatic operation caused by a variation of the fluid pressure, but in a manner dependent upon the fluid pressure. If there is practically no fluid pressure in the inlet pipe to the valve, the valve will not remain open after being manually opened, but if there is such fluid pressure the valve will remain open when opened. If, however, while the valve is open, or the plug 4 is raised from its seat, the fluid pressure decreases sufficiently, the plug 4 will be automatically seated, thus tightly closing the valve.

After the valve has been manually closed the diaphragm 23 will remain in the extended position 28 if there is no escape for the fluid from the holes 10 10 along the bore 7 to either the opening 34 or the outlet passage 3, but if there is such an escape the diaphragm may take the retracted position 23 due to the decrease of pressure in the hole 9 and chamber 24. The position of the diaphragm 23 at this time is, however, immaterial in the form of valve illustrated, because the weight of the parts 38 38 26 26 holds the ends 21 21 of the arms 12 12 inwardly as shown in Fig. 1, so that the valve cannot be accidentally opened.

I wish it to be understood that the spring 32 may be adjusted so as to automatically close the valve at any predetermined fluid pressure, or at zero pressure. It will be readily seen that with the form of link joint used between the pivots 25 25, a very slight pressure on the diaphragm 23 may be made to hold the valve open. It will be readily seen that by suitably proportioning the various parts of the apparatus, the extent of operation of the arms 12 12 may be varied as desired. Of course the diaphragm may be made of various suitable materials, and the size of same proportioned to give the required effect. I also wish it to be understood that this invention may be used with various types, styles and sizes of valves, and in various modes of application.

I do not wish to limit this invention to the exact construction, arrangement, or various details herein shown, as various modifications thereof may be made or utilized without departing from the scope of the appended claims.

What I claim as my invention is:

1. A valve having a plug normally seated in a seat, means for manually raising the plug from its seat, a diaphragm carried by the plug, the latter having a passage there-

- through to the diaphragm whereby the diaphragm is connected with the inlet passage of the valve when the plug is unseated, mechanism under control of the diaphragm for holding the plug out of its seat, and spring mechanism tending to seat the plug, a diminution of the fluid pressure causing the diaphragm to permit the said spring mechanism to automatically seat the plug.
10. 2. A valve having a plug and a seat therefor, means whereby the plug may be raised from its seat and turned to control the valve passage, a pair of arms for holding the plug out of its seat, a coil spring surrounding the plug and tending to seat same, a diaphragm carried by one end of the plug, the latter having a passage longitudinally therethrough whereby the diaphragm is connected with the inlet passage of the valve when the plug is unseated, and mechanism under control of the diaphragm whereby the said arms are held against operation when the plug is out of its seat, whereby the plug is held out of its seat, a diminution of the fluid pressure causing the diaphragm to permit of operation of the mechanism under its control whereby the said spring automatically seats the plug.
30. 3. In a valve having a plug and a seat therefor, a pair of pivoted arms for holding the plug out of its seat, the ends of the arms being crossed over past each other whereby accidental striking thereof acts against operating them.
35. 4. In a valve of the character specified, valve-controlling mechanism comprising a pair of pivoted arms, the said arms being crossed over each other whereby accidental striking thereof acts against operating them.
40. 5. In a valve having a plug and a seat therefor, and means operable for unseating the plug and then turning it to control the valve passage, pressure-controllable mechanism for holding the plug out of its seat, and spring-controlled mechanism tending to seat the plug, a diminution of the controlling pressure permitting the plug to be automatically seated.
50. 6. In a valve having a plug and a seat therefor, and means operable for unseating the plug and then turning it to control the valve passage, a pressure-controllable diaphragm and mechanism under control thereof for holding the plug out of its seat, and spring-controlled mechanism tending to seat the plug, a diminution of the controlling pressure permitting the plug to be automatically seated.
55. 7. In a valve of the character specified having a plug adapted to be given a plurality of operations of different characters to control the valve passage, a pressure-controllable diaphragm and mechanism under control thereof for automatically giving the said plug one of the said operations upon a diminution of the controlling pressure.
8. In a valve of the character specified having mechanism adapted to be given a plurality of operations of different characters to control the valve passage, a pressure-controllable diaphragm controlling the said mechanism and permitting it to be given one of the said operations upon a diminution of the controlling pressure.
9. A valve having a plug normally seated in a seat, means for manually raising the plug from its seat, means for holding the plug out of its seat including, a diaphragm carried by the plug, the latter having a passage therethrough to the diaphragm whereby the diaphragm is connected with the inlet passage of the valve when the plug is unseated, and spring mechanism under control of the diaphragm and tending to seat the plug, a diminution of the fluid pressure causing the diaphragm to permit the said spring mechanism to automatically seat the plug.
10. A valve having a plug and a seat therefor, means whereby the plug may be raised from its seat and turned to control the valve passage, a pair of arms for holding the plug out of its seat, spring mechanism tending to seat the plug, a diaphragm carried by one end of the plug, the latter having a passage longitudinally therethrough whereby the diaphragm is connected with the inlet passage of the valve when the plug is unseated, and mechanism having a toggle joint under control of the diaphragm whereby the said arms are held against operation when the plug is out of its seat, whereby the plug is held out of its seat, a diminution of the fluid pressure causing the diaphragm to permit of operation of the said toggle joint and the said arms, whereby the said spring mechanism automatically seats the plug.
11. A valve having a casing with an annular passageway therein, a valve plug having a pair of arms associated therewith and adapted to work in the said passageway, and pressure-controllable mechanism controlling the said arms and thereby controlling the operation of the said plug.
12. A valve having a casing with an annular passageway therein, a valve plug having a pair of arms associated therewith and adapted to work in the said passageway, spring mechanism adapted to operate the said plug, and pressure-controllable mechanism controlling the said arms and thereby controlling the operation of the said plug.
13. A valve having a plug, a body portion, a pair of arms cooperating with the body portion for maintaining the plug in a predetermined position, and pressure-controllable mechanism controlling the said

arms and thereby controlling the operation of the said plug.

14. A valve having a plug, a body portion, a pair of arms coöperating with the body portion for maintaining the plug in a predetermined position, spring mechanism adapted to operate the said plug, and pressure-controllable mechanism controlling the said arms and thereby controlling the operation of the said plug.

15. In a valve having a casing, valve-controlling mechanism having a pair of arms coöperating with the valve casing, the said arms being crossed over each other whereby accidental striking thereof acts against operating them.

16. In a valve having a plug and a body portion, a pair of arms coöperating with the body portion for maintaining the plug in a predetermined position, the said arms being crossed over each other whereby accidental striking thereof acts against operating them.

17. In a valve having a plug and a seat therefor, means whereby the plug may be raised from its seat to open the valve, a pair of arms coöperating with the valve casing for holding the plug out of its seat, spring mechanism tending to seat the plug, a diaphragm carried by one end of the plug, the latter having a passage longitudinally therethrough whereby the diaphragm is connected with the inlet passage of the valve when the plug is unseated, and link mechanism having a toggle joint under control of the diaphragm whereby the said arms are held against operation when the plug is unseated, a diminution of the fluid pressure

causing the diaphragm to permit of operation of the mechanism under its control whereby the said spring mechanism is permitted to seat the plug.

18. In a valve having a plug and a seat therefor, means whereby the plug may be raised from its seat to open the valve, a pair of arms for holding the plug out of its seat, spring mechanism tending to seat the plug, a diaphragm carried by one end of the plug, the latter having a passage longitudinally therethrough whereby the diaphragm is connected with the inlet passage of the valve when the plug is unseated, and mechanism under control of the diaphragm whereby the said arms are held against operation when the plug is unseated, a diminution of the fluid pressure causing the diaphragm to permit of operation of the mechanism under its control whereby the said spring mechanism is permitted to seat the plug.

19. In a valve of the character specified having mechanism adapted to be given a plurality of operations of different characters to control the valve passage, pressure-controllable mechanism controlling one of the said operations of the first said mechanism and permitting the latter to be given this operation upon a diminution of the controlling pressure.

As inventor of the foregoing I hereunto subscribe my name this 15th day of September, 1909.

FREDERICK R. PARKER.
